UNITED STATES PATENT OFFICE

MARY BOWERS, NOW BY MARRIAGE MARY BOWERS WALSWORTH, OF ANGORA,
NEBRASKA

BED CONSTRUCTION

Application filed April 10, 1929. Serial No. 354,084.

This invention relates to new and useful improvements in beds and more particularly to a novel mattress and spring unit for beds.

The principal object of this invention is to provide a combination mattress and spring construction for beds wherein a fresh mattress surface may be provided whenever the occasion arises without the necessity of removing the mattress from the bed.

10 Another important object of the invention is to provide a bed structure including a novel spring and mattress construction which can be manipulated in a quick and convenient manner.

15 These and other objects of the invention will become more apparent to the reader after considering the invention as described and claimed hereinafter.

In the drawings:

20 Figure 1 represents a top plan view of the novel bed construction partly broken away to show the spring.

Figure 2 is a fragmentary side elevation of the improved bed construction.

25 Figure 3 represents a longitudinal sectional view through one of the rolls upon which the improved mattress and spring construction is mounted.

Figure 4 represents a horizontal sectional view through one of the bed posts.

30 Figure 5 represents a fragmentary vertical sectional view through one of the posts and showing in side elevation the means for supporting and adjusting the rolls.

35 Referring to the drawings wherein like numerals designate like parts, it will be seen that for the purpose of illustration a bed comprising the four posts 3 and the connecting rails 4 are shown to properly illustrate the 40 association therewith of the present invention. Each post 3 as shown in Figure 5 has a hook member 5 secured thereto by a pair of screws 6-6, which may be fed into the post or outwardly thereof to vary the spaced relation of the foot member 5 with respect thereto in the operation of tightening or loosening the hereinafter described combination mattress and spring construction.

The mattress and spring construction includes an endless web 7 of suitable foraminous

material, which is adapted to be trained over a pair of rolls 8-8. Arranged around the web 7 is an endless mattress 9, constructed of suitable material. The rolls 8 are arranged each on a suitable polygonal shaped bar 10 which has its ends 11 reduced and rounded for engagement within the hook members 5, in the manner shown in dotted lines in Figure 5. The rounded ends are also squared at their extremities to permit the engagement therewith of a crank handle 12.

It will thus be seen that by disposing the rolls through the mattress and spring structure substantially in the manner shown in Figure 2 and the rounded ends of the rolls 65 engaged within the hooks 5, the mattress and spring construction may be stretched to the proper tautness by adjusting the screws 6-6.

Furthermore, it is to be understood that various changes in the specific, shape, size and materials may be made without departing from the spirit and scope of the invention as claimed hereinafter.

What is claimed as new is:

1. A bed construction of the character described comprising a bedstead, a pair of rolls rotatably mounted on said bedstead, an endless web of relatively strong material trained over said rolls, and an endless mattress arranged around said web. 75

2. A bed construction of the character described comprising a bedstead, a pair of rolls rotatably mounted on said bedstead, an endless web of open mesh material trained over said rolls, and a mattress attached to the said 85 web.

In testimony whereof I affix my signature
MARY BOWERS.
